UNITED STATES PATENT OFFICE.

EUGENE SCHNEIDER, OF PARIS, FRANCE, ASSIGNOR TO SCHNEIDER & CIE., OF PARIS, FRANCE, A LIMITED JOINT-STOCK COMPANY OF FRANCE.

APPARATUS FOR PRODUCING SELF-HOOPING EFFECTS IN METAL TUBES.

Application filed June 29, 1923. Serial No. 648,559.

To all whom it may concern:

Be it known that I, EUGENE SCHNEIDER, a citizen of the Republic of France, residing at Paris, France, have invented new and useful Improvements in Apparatus for Producing Self-Hooping Effects in Metal Tubes, which is fully set forth in the following specification.

The present invention has for its subject an apparatus for producing hooping effects in metal tubes of great resistance by hydraulic pressure exerted upon the inner wall of the tube, said tube being closed by two outside plates which are connected together either by means of an axial tie-rod or by exterior tie-rods.

The new apparatus is characterized by a special method for effecting the closing of the tubes. This method secures a perfectly liquid-tight joint between the tube to be hooked and the supporting plates during the whole operation, and does not involve the use of joints between the inner wall of the tube and obturators which penetrate into the tube, the suppression of the said obturators and of the corresponding joints permitting the hooping operation to take place, over the total length of the tube.

Different forms of construction of the invention are shown by way of example in the accompanying drawings:

Figure 1 shows apparatus suitable for hooping metallic tubes in the vertical position.

Figures 2-2^A together show apparatus suitable for hooping metallic tubes in the horizontal position.

Figure 3 is a diagrammatic view of one end of the apparatus shown in Fig. 2, with the parts in the position they assume towards the ends of the hooping operation.

Figures 4-4^A together show a modification of the arrangement shown in Fig. 2.

Figure 1 shows in longitudinal sectional elevation the two extremities of the tube D which is to be hooped. Said tube D is arranged in position vertically between two plates A and B which are interconnected by means of the exterior tie-rods C.

According to the invention the closing of the interior space is effected, at least for one of the plates A, by liquid-tight annular joints E and F, interposed, the one F between the plate A and an intermediate

sleeve G, the other between this sleeve and the edge d of the tube. The diameters (e and f) of these two annular joints are such that the area of the exterior edge of the sleeve which is subjected to the pressure of the liquid is substantially greater than the area of the interior edge of said sleeve which is subjected to the pressure of the liquid.

For the opposite plate B it is sufficient to effect the joint by a ring b interposed between the said plate and the corresponding edge (d¹) of the tube D.

When it is desired to effect the hooping operation, the liquid under pressure is admitted, in known manner, through the plate A for example, so that it fills the inside of the tube D and the interior of the sleeve G. During the admission of the liquid under pressure, the air may be allowed to escape through a passage a which is provided in the plate A and is adapted to be closed at the end of the filling operation by means of a stopper a¹.

It is easy to see that, during the whole of the hooping operation, the liquid under pressure penetrates on the one hand between the edge g of the sleeve G and the bottom of the plate A, the leakage of the liquid to the outside being prevented by the joint F; on the other hand, the liquid penetrates between the edge g¹ of the sleeve G and the edge d of the tube D, the leakage of the liquid being prevented by the joint E. The diameter f being substantially greater than the diameter e, the total pressure of the liquid which is exerted between A and G is substantially greater than that which is exerted between G and D. It thereby follows that this arrangement constitutes the differential joint which ensures at all times that all of the joints E, F and b shall be completely liquid-tight, the pressure simply tending to lengthen the tie-rods C.

In the example which has just been described, it is assumed that the tube D is subjected to the hooping operation when in the vertical position.

When it is desired to hoop tubes in the horizontal position, then in combination with the differential joint arrangement effected by the use of an intermediate sleeve G, there is also preferably used an apparatus for centering such as that represented in longitudinal axial section in Figs. 2-2^A.

In this example, G denotes an intermediate sleeve similar to that used in the preceding example; F denotes the annular joint, of diameter f , between this sleeve and the bearing plate A, and E denotes the annular joint, of diameter e , between the interior edge g^1 of the sleeve G and the edge d of the tube D; b denotes the annular joint directly interposed between the plate B and the corresponding edge d^1 of the tube D.

According to the invention, the tube D is centered at its two extremities by two conical obturators H and I, of which the one H is movable within the intermediate sleeve G, while the other I, is movable within a recess provided in the bearing plate B.

Towards the exterior and behind the conical head which penetrates into the corresponding mouth of the tube D each of these obturators comprises two cylindrical parts of different diameters. It is in this way that the obturator H comprises a cylindrical part of diameter h near its conical head, and beyond, towards the exterior, a cylindrical part of greater diameter h^1 . In the same way, beyond its conical head, the obturator I comprises two cylindrical parts of diameters i and i^1 respectively. Further, the sleeve G, and the recess provided in the plate B each comprise two cylindrical parts of corresponding diameters, so that between A and G there may be arranged the two annular joints J and J^1 of diameters h and h^1 respectively, while between the obturator I and the wall of the recess there may be arranged the annular joints K and K^1 of diameters i and i^1 respectively.

Each of these obturators I and H constitutes a true differential piston. It is essential that the liquid admitted through the truncated obturators H, I should pass between these obturators and the inner face of the outer plates A and B; practically, this is taken care of by a very slight play between these parts. However, there are provided at various points in the said obturators, and also in the sleeve G, radial grooves H', I', G' which serve to distribute the liquid between the faces of the sleeve and obturator and the inner faces of the plates A and B. It is understood that under the influence of the liquid pressure which is exerted on the exterior edge of the obturator H over a circular section of diameter h^1 greater than the diameter h , there will be a constant tendency to drive the said obturator towards the interior, and to hold it in contact with the tube D along the circumference of a circle. In the same way the obturator I constitutes a differential piston which will be constantly driven towards the interior and maintained in contact with the corresponding mouth of the tube D. When, under the effect of the pressure, the interior diameter of the tube D increases, the obtura-

tors will be progressively displaced towards the interior, the obturator H for example finally coming to occupy a position such as that diagrammatically indicated in Figure 3.

Figures 4-4^A show in longitudinal sectional elevation, a modification in which the assembly between the two bearing plates A and B is effected by means of an axial tie-rod L, constituting a hooping mandrel. In this example it is assumed that an intermediate sleeve G is used both in the case of the plate A and also in the case of the plate B. In this modification the obturators H and I are axially hollowed out in order to permit the axial tie-rod L to pass through them. As in the preceding example, at all times during the operation the centering is automatically ensured while the liquid is given entirely free access to the inside surface of the tube over the whole extent of the tube to be hooped. In Figs. 4-4^A, the sectional view of the upper part is made in the plane of one of the liquid distributing grooves G'; at the lower part of these figures the sectional plane passes between such grooves.

Having now particularly described and ascertained the nature of our said invention and in what manner the same is to be performed, we declare that what we claim is:

1. In an apparatus for subjecting metal tubes to hydraulic pressure, the combination of two plates at opposite ends of the tube, tie-rod connections between said plates, a sleeve intermediate one of said plates and one end of the tube, annular liquid-sealing joints respectively between said sleeve and plate and between said sleeve and tube, the diameter of one of these joints being substantially greater than that of the other, whereby the two faces of the sleeve are subjected to differential pressure.

2. In an apparatus for subjecting metal tubes to hydraulic pressure, the combination of two plates at opposite ends of the tube, tie-rod connections between said plates, a sleeve intermediate one of said plates and one end of the tube, annular liquid-sealing joints respectively between said sleeve and plate and between said sleeve and tube, the diameter of one of these joints being substantially greater than that of the other, whereby the two faces of the sleeve are subjected to differential pressure, and an annular liquid-sealing joint between the other plate and the end of the tube.

3. In an apparatus for subjecting metal tubes to hydraulic pressure, the combination of two plates at opposite ends of the tube, tie-rod connections between said plates, a sleeve intermediate one of said plates and one end of the tube, annular liquid-sealing joints respectively between said sleeve and plate and between said sleeve and tube, the diameter of the joint

between the sleeve and plate being substantially greater than the diameter of the joint between the sleeve and tube.

4. In an apparatus for subjecting metal tubes to hydraulic pressure, the combination of two plates at opposite ends of the tube, tie-rod connections between said plates, a sleeve intermediate one of said plates and one end of the tube, annular liquid-sealing joints respectively between said sleeve and plate and between said sleeve and tube, the diameter of the joint between the sleeve and plate being substantially greater than the diameter of the joint between the sleeve and tube, and an annular liquid-sealing joint between the other plate and the end of the tube.

5. In an apparatus for subjecting metal tubes to hydraulic pressure, the combination of two plates at opposite ends of the tube, tie-rod connections between said plates, a sleeve intermediate one of said plates and one end of the tube, annular liquid-sealing joints respectively between said sleeve and plate and between said sleeve and tube, the diameter of the joint between the sleeve and plate being substantially greater than the diameter of the joint between the sleeve and tube, a centering obturator carried by the sleeve and entering one end of the tube, and a second centering obturator carried by the other plate and entering the opposite end of the tube.

6. In an apparatus for subjecting metal tubes to hydraulic pressure, the combination of two plates at opposite ends of the tube, tie-rod connections between said plates, a sleeve between each of said plates and one end of the tube, and annular liquid-sealing joints respectively between said sleeves and plates and between said sleeves and tube ends, the diameters of the joints between the plates and sleeves being substantially different from those of the joints between the sleeves and tube ends.

7. In an apparatus for subjecting metal tubes to hydraulic pressure, the combination of two plates at opposite ends of the tube, tie-rod connections between said plates, a sleeve between each of said plates and one end of the tube, and annular liquid-sealing joints respectively between said sleeves and plates and between said sleeves and tube ends, the diameters of the joints between the plates and sleeves being substantially greater than those of the joints between the sleeves and tube ends.

8. In an apparatus for subjecting metal tubes to hydraulic pressure, the combination of two plates at opposite ends of the tube, tie-rod connections between said plates, a sleeve between each of said plates and one end of the tube, centering ob-

turators carried by the sleeves and entering opposite ends of the tube, and annular liquid-sealing joints between said sleeves and plates and between said sleeves and the ends of the tube, the diameters of the joints between the sleeves and plates being substantially different from those of the joints between the sleeves and the tube ends.

9. In an apparatus for subjecting metal tubes to hydraulic pressure, the combination of two plates at opposite ends of the tube, tie-rod connections between said plates, a sleeve between each of said plates and one end of the tube, centering obturators carried by the sleeves and entering opposite ends of the tube, and annular liquid-sealing joints between said sleeves and plates and between said sleeves and the ends of the tube, the diameters of the joints between the sleeves and plates being substantially greater than those of the joints between the sleeves and the tube ends.

10. In an apparatus for subjecting metal tubes to hydraulic pressure, the combination of two plates at opposite ends of the tube, a central tie-rod connection between said plates, a sleeve intermediate each of said plates and the adjacent tube end, two centering obturators one carried by each sleeve and entering the opposite ends of the tube, annular fluid-sealing joints between each plate and its adjacent sleeve and between each sleeve and the adjacent tube end, the joints between the plates and sleeves being of substantially greater diameters than those of the joints between the sleeves and tube ends.

11. In an apparatus for subjecting metal tubes to hydraulic pressure, the combination of two plates at opposite ends of the tube, a central tie-rod connection between said plates, a sleeve intermediate each of said plates and the adjacent tube end, two centering obturators one carried by each sleeve and entering the opposite ends of the tube, annular fluid-sealing joints between each plate and its adjacent sleeve and between each sleeve and the adjacent tube end, the joints between the plates and sleeves being of substantially greater diameters than those of the joints between the sleeves and tube ends, and two annular liquid-sealing joints between the respective obturators and sleeves the diameters of said joints adjacent the outer faces of the sleeves being greater than those adjacent the inner faces thereof.

In testimony whereof I have signed this specification.

EUGENE SCHNEIDER.
